(57) **CLAIM**

The ornamental design for a watch bracelet, as shown and described.

DESCRIPTION

FIG. 1 is a perspective view of a watch bracelet in an open position showing the new design;

FIG. 2 is a side view of the watch bracelet shown in FIG. 1, the other side view being a mirror image thereof;

FIG. 3 is a top view of the watch bracelet shown in FIG. 1; FIG. 4 is a bottom view of the watch bracelet shown in FIG. 1; and,

FIG. 5 is a rear perspective view of the watch bracelet shown in FIG. 1, in a closed position.

The broken line showing of a watchcase, screws, and clasp mechanism is for illustrative purposes only and forms no part of the claimed design.
